[57] CLAIM

The ornamental design for a fluorescent lamp ballast enclosure, as shown and described.

DESCRIPTION

FIG. 1 is a top left front isometric view of a fluorescent lamp ballast enclosure showing my new design;

FIG. 2 is a bottom rear isometric view thereof;

FIG. 3 is a front view thereof;

FIG. 4 is a bottom view thereof;

FIG. 5 is a top view thereof;

FIG. 6 is a rear view thereof;

FIG. 7 left side view thereof shown at an enlarged scale; and,

FIG. 8 is a right side view thereof shown at an enlarged scale.
